ABSTRACT OF THE DISCLOSURE

A vacuum pump apparatus having a rotor with pumping chambers into which a pumping fluid is injected and discharged by centrifugal force. The pumping chambers are sealed in a fluid bath and periodically register with an inlet port thereby providing a pumping action.

This invention relates generally to vacuum pumps and, more particularly, to a fluid sealed, rotary vacuum pump.

Mechanical vacuum pumps of various types have been developed for use in the low to medium vacuum range between atmosphere and 10^{-2} torr. The various types include piston pumps, bellows pumps, rotary piston pumps, gear pumps, centrifugal pumps, etc. Although such pumps operate effectively in many vacuum applications, their cost has been undesirably high primarily because of the close manufacturing tolerances required for establishing sufficiently tight vacuum seals between the pump's moving parts. Furthermore, because of this tolerance requirement, the inherent mechanical wear between moving parts materially shortens the pump's operating life.

The object of this invention, therefore, is to provide an improved mechanical vacuum pump which is effective in the low and medium vacuum ranges and which alleviates requirements for close operating tolerances between moving parts thereby both reducing manufacturing costs and extending the useful life of the pump.

One feature of this invention is the provision of a mechanical vacuum pump having a rotor which is closely confined axially by the end walls of a pump casing and which defines a plurality of radially extending, outwardly opening pumping chambers. The pump casing includes a circumferentially spaced pumping port and fluid inlet port which sequentially and periodically register with inner portions of the pumping chambers during each revolution of the rotor and a discharge port spaced radially outwardly from the fluid inlet and pumping ports. Fluid injected into the pumping chambers through the fluid inlet port is expelled outwardly by centrifugal force thereby removing the chamber's gas content for discharge through the discharge port. The void created in the pumping chamber behind the expelled fluid produces a pumping action on the pumping port upon subsequent registry therewith. By utilizing the injected fluid as a pumping mechanism, the requirement for close tolerances between moving mechanical parts is eliminated. This lessens manufacturing costs by permitting the use of relatively inexpensive molded parts rather than closely machined metallic parts.

Another feature of this invention is the provision of a vacuum pump of the above featured type including a reservoir housing filled with a body of sealing fluid under which the fluid inlet and discharge ports are submerged. The pump of this construction possesses an extremely simple configuration requiring a minimum of separate components.

Another feature of this invention is the provision of a vacuum pump of the above featured type wherein the pump casing is completely submerged in the body of the sealing fluid and the rotor is rotated in a substantially horizontal plane by a shaft which passes through the

body of sealing fluid. In this arrangement the required number of pump parts is further reduced and the body of sealing fluid provides a fluid seal for the pump casing.

Another feature of this invention is the provision of a vacuum pump of the above featured type wherein the radial spacing between the outer periphery of the rotor and the side walls of the pump casing varies substantially about the circumference of the rotor. The variable spacing produces distinct operating pressure regions within the pump casing thereby beneficially affecting pump performance.

Another feature of this invention is the provision of a vacuum pump of the above featured type wherein the discharge port communicates directly with a pump casing volume located between the rotor and the casing side walls and wherein the spacing between the fluid inlet port and the casing side wall is greater than the spacing between the pumping port and the casing walls. It has been found that pump performance is optimized with this particular arrangement of the various ports.

Another feature of this invention is the provision of a vacuum pump of the above featured type wherein the rotor is a unitary body having slots which form the pumping chambers. The use of a unitary rotor further reduces cost of simplifying both manufacturing and assembly requirements.

Another feature of this invention is the provision of a vacuum pump of the above featured type wherein the rotor possesses between the pumping chambers solid portions of substantial circumferential width which create with the casing end walls relatively lengthy vacuum seals between the individual pumping chambers thereby improving pump performance.

These and other features and objects of the present invention will become more apparent upon a perusal of the following specification taken in conjunction with the accompanying drawings wherein:

FIG. 1 is an elevational view, partially in cross-section, illustrating a preferred pump embodiment of the invention;

FIG. 2 is a cross-sectional view, partially cut-away, taken along lines 2—2 in FIG. 1; and

FIG. 3 is a cross-sectional view taken along lines 3—3 in FIG. 2.

Referring now to FIG. 1, there is shown the reservoir housing 11 including the hollow cylinder 12 closed by the circular bottom wall 13 and the circular top wall 14. Positioned within the housing 11 is the vacuum pump casing 15 having side walls formed by the hollow cylinder 16 and end walls formed by the circular cover plate 17 and the bottom wall 13 of the housing 11. The pump casing 15 is secured by cap screws 18 which pass through an outwardly projecting flange portion of the cover plate 17 and threadedly engage the bottom wall 13. Mounted on the top wall 14 is the electric motor 19 having the shaft 21 which extends through apertures in the top wall 14 and cover plate 17 and is engaged for rotation with the rotor 22. The pumping inlet tube 23 is connected to the pump casing 15 and extends through an opening in the top wall 14.

As shown more clearly in FIGS. 2 and 3, the circumferential periphery of the pump rotor 22 is interrupted by a plurality of uniformly spaced slots which form pumping chambers 24 opening outwardly into the volume between the rotor 22 and the cylindrical side wall 16. The axial length of the rotor 22 is substantially equal to the spacing between the pump's end walls 13 and 17 so as to form relatively gas tight seals therewith between the pumping chambers 24. However, satisfactory performance is obtained with clearances between the rotor 22 and the end walls 13 and 17 in the order of .004-.015

inch. Clearances of this order are substantially greater than the typical .001 inch and smaller clearances required in conventional vacuum pumps. To further enhance the sealing capability of the closely spaced rotor 22 and side walls 13 and 17, the circumferential widths of the rotor solid portions separating the pumping chambers 24 are preferably relatively large as shown in FIG. 2. In this regard it has been found desirable from standpoints of both performance and production, to utilize a rotor 22 which is a slotted unitary member and can be easily produced by conventional molding or casting of plastic or metallic substances.

The motor shaft 21 extends through a central opening 25 in the end wall 17 and into a central aperture 26 in the rotor 22. Rotational coupling between the motor shaft 21 and the rotor 22 is provided by a ridge 27 in the aperture 26 which engages a longitudinal key slot in the shaft 21. Also located in the pump casing end wall 17 are the inlet pumping port 31, the fluid inlet port 32 and the discharge port 33. The inlet pumping port 31 receives the inlet tube 23 while the fluid inlet port 32 and the discharge port 33 provide direct communication between the interior of the pump casing 15 and the surrounding volume within the reservoir housing 11.

The pumping port 31 and the fluid inlet port 32 are equally spaced radially from the center of the rotor 22 and are so positioned as to periodically register with the interior portions of the pumping chambers 24 during rotation of the rotor 22. Conversely, the discharge port 33 is spaced farther from the rotor center so as to communicate with the open volume 35 formed by the gap between the rotor periphery and the casing side wall 16. As shown, the size of this gap varies substantially about the circumference of the rotor because of its eccentricity with the casing side wall 16. Preferably, the fluid inlet port 32 is so positioned as to be spaced farther from the casing side wall 16 than is the inlet pumping port 31.

Prior to operation, the reservoir 11 is filled with a suitable sealing fluid 38 through an opening 39 in the top wall 14. The sealing fluid 38 can be any of a wide variety of fluid substances capable of functioning in the manner described below. However, because extensive lubrication is not required, water with its desirable low cost and low viscosity characteristics is uniquely suited for use with the device. Examples of other suitable fluids include mechanical pump oils, diffusion pump oils, mercury, etc. After filling the reservoir 11 with the pumping fluid 38 and connecting the pumping tube 23 with a chamber (not shown) to be evacuated, the electric motor 19 is energized from a conventional power source (not shown) to produce rotation of the shaft 21 and attached pump rotor 22.

It is difficult to provide from a strictly technical basis a full and exact explanation of the pumping phenomenon which occurs in the pump casing 15. Nevertheless, under actual tests, the pump configuration shown in FIGS. 2 and 3 has exhibited remarkable pumping performance capabilities and although a detailed theoretical explanation of the pumping phenomenon will not be attempted, a rather general and theoretical explanation of the observed pumping action is presented below.

The revolving rotor 22 throws pumping fluid 38 outwardly from the center of the casing 17 by centrifugal force, producing a ring of sealing fluid revolving within the casing 17 and against the side wall 16 at rotor speed. Because of the eccentricity between the rotor 22 and the casing cylinder 16, the spacing between the fluid ring and the rotor center will vary about the circumference of the pump. Thus, the fluid free volume in an individual pumping chamber 24 will vary during a rotational cycle. For example, the fluid free inner volume of the pumping chamber 24 is large adjacent the discharge port 33 where the spacing between the rotor 22 and the casing side wall 16 is large but is smaller at a position diametrically opposite thereto where the revolving fluid ring is forced into the pumping chamber by the closely adjacent side

wall 16. As each pumping chamber 24 registers with the fluid inlet port 32 a bead of pumping fluid 38 is injected from the reservoir 11. Centrifugal force drives the bead outwardly creating behind it a void formed by the bead, the walls of the pumping chamber and the casing end walls 13 and 17. The air ahead of the fluid bead is forced into a relatively high pressure region existing between the fluid bead and the revolving fluid ring. This pressure region somewhat retards outward movement of the fluid bead such that before discharge from the pumping chamber it will reach a circumferential position wherein the revolving fluid ring is being forced into the pumping chamber as a result of the diminished spacing between the rotor 22 and the casing side wall 16. At this time the liquid ring will seal the outer opening of the pumping chamber so as to maintain therein the void created by the injected fluid bead. Upon further rotation of the rotor 22 this void will register with the pumping inlet port 31 as the fluid ring is again withdrawing from the pumping chamber. The registry of the void and the inlet port 31 produces a pumping action on the attached pumping inlet line 23, and air entering the port 31 will be immediately discharged upon alignment of the chamber with the fluid inlet port 32 in the manner just described. Air forced by the fluid bead into the volume 35 and sealing fluid excess created by the bead's injection are forced by the existing pressures within the pump casing 17 outwardly through the discharge port 33 into the fluid body 38. The above pumping action occurs in each pumping chamber 24 during each revolution thereof with the rotor 22.

In a tested embodiment of the pump shown in FIGS. 2 and 3, the cylindrical casing 16 had an internal diameter of $25\frac{1}{4}$ inches, the rotor 22 had a diameter of $1\frac{3}{4}$ inches and an axial length of .575 inch, and the minimum radial spacing between the rotor 22 and the casing side wall 16 was about $\frac{1}{16}$ inch. This pump was successfully operated at a rotor speed of 5800 revolutions per minute.

Obviously, many modifications and variations of the present invention are possible in light of the above teachings. It is, therefore, to be understood that within the scope of the appended claims the invention can be practiced otherwise than as specifically described.

What is claimed is:

1. A vacuum pump apparatus comprising a pump casing having side wall means closed by spaced apart end walls, a rotor adapted for rotation between said end walls, drive means adapted to produce rotation of said rotor, said rotor defining at least one generally radially extending outwardly opening pumping chamber, an inlet pumping port in said casing adapted to periodically register with the inner portion of said pumping chamber during rotation of said rotor, a fluid inlet means adapted to inject fluid through an inlet port into the inner portion of said pumping chamber, said fluid inlet port and said pumping port being circumferentially spaced so as to sequentially register during rotation of said rotor with the inner portion of said pumping chamber, and a discharge port located in said casing and spaced radially outwardly from said inlet pumping port so as to receive fluid discharged outwardly by said pumping chamber.

2. A vacuum pump apparatus according to claim 1 wherein the outer periphery of said rotor possesses a plurality of slots that define a plurality of generally radially extending outwardly opening pumping chambers having inner portions adapted to periodically and sequentially register with said inlet pumping port and said fluid inlet port.

3. A vacuum pump apparatus according to claim 2 wherein the rotor solid portions between said slots have a thickness substantially equal to the spacing between said end walls so as to form therewith relatively gas tight seals.

4. A vacuum pump apparatus according to claim 3 wherein said fluid inlet port is located in one of said end

walls and positioned so as to periodically register with the inner portions of said pumping chambers during rotation of said rotor.

5. A vacuum pump apparatus according to claim 4 wherein said drive means comprises a shaft extending into said casing and connected for rotation with said rotor.

6. A vacuum pump apparatus according to claim 5 including a reservoir housing means adapted to contain a body of sealing fluid and wherein said fluid inlet port and said discharge port are in fluid communication connection with the body of sealing fluid.

7. A vacuum pump apparatus according to claim 6 wherein said fluid inlet port and said discharge port are adapted to be submerged in the body of sealing fluid.

8. A vacuum pump apparatus according to claim 7 wherein said shaft passes through the body of sealing fluid, and said rotor is adapted for rotation in a substantially horizontal plane.

9. A vacuum pump apparatus according to claim 8 wherein a bottom wall of said reservoir housing forms one of said pump casing end walls, and said inlet pumping port, said fluid inlet port and said discharge port comprise apertures in the opposite pump casing end wall.

10. A vacuum pump apparatus according to claim 6 wherein the radial spacing between the outer periphery of said rotor and said pump casing side wall means varies substantially about the circumference of the rotor.

11. A vacuum pump apparatus according to claim 10 wherein said discharge port directly communicates with a volume located between said rotor and said pump casing side wall means.

12. A vacuum pump apparatus according to claim 11 wherein the spacing between said fluid inlet port and said casing side wall means is greater than the spacing between said inlet pumping port and said casing side wall means.

13. A vacuum pump apparatus according to claim 12 wherein said casing side wall means comprises a cylinder and the rotational axis of said rotor is eccentric to said cylinder so as to create the variations in said radial spacing.

14. A vacuum pump apparatus according to claim 6 wherein the said rotor solid portions have substantial circumferential widths so as to provide relatively large circumferential separations between said pumping chambers.

15. A vacuum pump apparatus according to claim 14 wherein said rotor is a unitary body having said slots which form said pumping chambers.

16. A vacuum pump apparatus comprising a pump casing having side walls means closed by spaced apart end walls, a rotor adapted for rotation between said end walls, drive means adapted to produce rotation of said rotor, said rotor defining at least one generally radially extending outwardly opening pumping chamber, an inlet pumping port in said casing adapted for gas communication with the inner portion of said pumping chamber during rotation of said rotor, a fluid inlet port adapted to inject fluid into the inner portion of said pumping chamber during periodic registration therewith, a discharge port located in said casing and spaced radially outwardly from said inlet pumping port so as to receive fluid discharged outwardly by said pumping chamber, and a reservoir housing means adapted to contain a body of sealing fluid that inundates said inlet fluid port and said discharge port.

17. A vacuum pump apparatus according to claim 16 wherein said rotor is adapted for rotation in a substantially horizontal plane, and said pump casing is adapted to be completely submerged by the body of sealing fluid.
